(57) **CLAIM**

The ornamental design for a medical needle assembly, substantially as shown and described.

DESCRIPTION

FIG. 1 is an overall perspective view of a bifurcated medical needle assembly with a pivoting safety shield showing our new design, the broken line shown for illustrative purposes only and forming no part of the claimed design; FIG. 2 is a top plan view thereof;

FIG. 3 is a side elevational view thereof;

FIG. 4 is a front elevational view thereof;

FIG. 5 is a rear elevational view thereof;

FIG. 6 is a bottom perspective view thereof with the pivoting safety shield in an open position;

FIG. 7 is a top perspective view of the bifurcated medical needle assembly shown with the pivoting safety shield in a closed, safety shielded position;

FIG. 8 is a side elevational view of the assembly as in FIG. 7 with the pivoting safety shield in a closed position; and,

FIG. 9 is a bottom elevational view of the assembly as in FIG. 7 with the pivoting safety shield in a closed position.

1 Claim, 5 Drawing Sheets
